ALTERNATING CURRENT REGULATING
MEANSClaude J. Holslag, South Orange, N. J., assignor
to Electric Arc, Inc., Newark, N. J.

Application April 1, 1942, Serial No. 437,103

3 Claims. (Cl. 315—144)

This invention relates to a current-regulating or adjusting structure which is adapted for use in regulating the current in an alternating current circuit, and especially for use in connection with arc welding.

In my Patent 2,192,312, issued March 5, 1940, I have shown various types of structures which are adapted for this purpose. This patent also points out the advantages of its disclosure over alternating current adjusting structures which I designed and used in years past.

I have found, from experience and further investigation, certain improvements over my prior structures, which improvements are set forth herein. While the structures of my Patent 2,192,312 disclose excellent current control means, I have found that the three-legged reactor, such as shown in Figure 1 of said patent, or the three-legged transformer shown in Figures 2 to 6 of said patent, still have certain drawbacks. For example, if the reactor or transformer is made what might be termed short and fat, the current change, when the movable core is shifted, is too abrupt. If the structure is long and thin, the movement of the shiftable core portion becomes excessive from bottom to top. These drawbacks may be overcome to some extent, as I have accomplished, by putting taps in the regulating coil or by making the regulating coil in groups so that these groups may be connected in series, multiple, or series multiple; or, still further, connecting the structures themselves as a whole, in series or in multiple, thereby getting numerous combinations of windings.

Where reactors such as shown in Figure 1 of my patent above mentioned are connected mechanically in series, physical balance of the movable core portions can be obtained, but the entire structure is large and cumbersome.

As heretofore stated, after much experience and experimentation with the above combinations, I have discovered improved ways of overcoming these drawbacks or what might be termed disadvantages. These improvements are illustrated rather diagrammatically in the enclosed drawing, wherein:

Figure 1 is a view showing an improved type of reactor, the same being a five-legged structure, the winding of which is connected to a current supply transformer, and both connected in an arc welding circuit.

Figure 2 is a fragmentary view of the bottom of the reactor shown in Figure 1.

Figure 3 is a diagrammatic view of a four-legged reactor which may be constructed like the

reactor of Figure 1, except that the central movable leg is circular in form.

Figure 4 is a bottom view of Figure 3 corresponding to Figure 2.

Figure 5 is a view of a further modified form of a five-legged reactor.

Figure 6 is a schematic view of a special adaptation of a polyphase gang arrangement of welding, utilizing three transformers such as shown in Figure 2 of my patent heretofore referred to.

Figure 7 is a view of a six-phase mother transformer, each phase of which may feed current to one or more of the reactors such as shown in Figures 1, 3 and 5.

15 In Figure 1, I illustrates the core of a supply transformer of the shell type having a primary winding 2 and a secondary winding 3 on the central leg of the core. One end of the secondary winding 3 is connected to a winding 4 that surrounds a movable middle leg 5 of a core having legs 6, 7, 8 and 9. Each of the legs 6—9 has a top inturned yoke end 10 to extend over the top part of the coil or winding 4 into close proximity to the movable core structure 5. The lower portions of the legs 6—9 have inturned ends 11

20 which preferably meet below the end of the movable leg 5 in a manner such as illustrated in Figure 2. The entire core structure, including the movable leg 5, is made up of suitable transformer lamination stock. The laminations are assembled in a manner so as to prevent undue heating of the various parts of the core. Likewise, the means for moving the middle core leg 5 may be of the pump-handle type such as shown in my patent previously referred to, wherein the handle may be operated manually or automatically by a suitable motor drive, but these details, various types of which have been used by me, are not necessary to make the present invention clear.

25 The opposite end of the secondary winding 3 and the opposite end of the coil 4 are connected to the arc electrodes.

In the reactor construction of Figure 1, by having four stationary legs with their respective yoke ends arranged as described, a better mechanical and electrical balance is obtained, as well as a reactor having a greater efficiency over a wide range of current which may be controlled thereby.

30 In Figure 3, three legs 12, 13 and 14 are shown with their yoke ends all in a straight line to better illustrate the application of the primary and secondary windings 15 and 16 thereto, but it is to be understood that the core parts 12, 13 and 14, with their yoke ends, are to be arranged preferably as

shown in Figure 1. The movable leg 17 may be a split tube carrying a bundle of relatively fine iron wire. The bottom yoke ends of the legs 12, 13 and 14 may be joined as shown in Figure 4, and if found necessary, the space 18 may be filled with suitable finely divided magnetic material housed to prevent its movement away from the allotted space. Primary leads 19 from the reactor extend to a suitable source of current supply.

In Figure 5 the core legs 6-9 are the same type of construction as in Figure 1, and likewise the yoke ends at both ends of the reactor are the same as the yoke ends 10 of Figure 1. In this form of reactor the fifth core leg is a split tube 17, the same as in Figure 3, filled with a bundle of relatively fine iron wire. The core leg 17 may be provided with attachments at either end for moving it back and forth within the winding 4. Preferably the core 17 is supported by suitable bearings 25 carried in support members 20 arranged at opposite ends of the structure.

In Figure 6, a three-phase transformer T supplies current to the primaries P of three reactor transformers 21, 22 and 23 which are arranged so that the third leg of each may form a junction similar to 18 of Figure 4, each secondary S being connected to its welding electrode E through its movable core coil 4. The legs 26 of each of the transformers 21, 22 and 23 may, as illustrated in Figure 6, be reduced in cross-sectional area, and the junction member 24 may be adjustable in and out, the same as the cores 5. By making the legs 26 of reduced area from the outer legs carrying the primary windings, the reactive effect of the movable core leg 24 will be greater and a simultaneous reaction on all the transformers and their respective arcs can be obtained.

If the source of supply is a six-phase arrangement, such as the six-phase mother transformer shown in Figure 7, then there will be six of the reactor transformers of Figure 6 preferably set at angles of sixty degrees. With this construction, where a very heavy current is required which is too much for one electrode, the load may be divided into two or more parts, depending on the number of phases used, and in this arrangement the electrodes E are positioned so as to get the effect of one large electrode. This arrangement lends itself admirably to gang welding wherein the electrodes are positioned in offset position so the arcs follow each other in sequence, somewhat like the furrows in a gang plow. If a large electrode were used, it would be connected to only one phase of a polyphase circuit and this would unbalance the system; whereas, by dividing the load in the manner described, the electrodes are smaller, and likewise the reactor transformers, thereby balancing the load on the supply system. While I have just

described the use of a reactive transformer in the gang welding arrangement shown in Figure 6, the reactors of Figures 1, 3 and 5 may likewise be arranged to give a similar result.

- 5 In Figure 7 I have shown one type of a six-phase mother transformer wherein only the secondary windings are shown, each phase of which may supply current to one or more of the reactors in a manner such as generally illustrated in my
10 Patent 2,025,207, but since this transformer per se forms no part of my present invention, it is not further described herein.

What I claim is:

1. A polyphase welding system including a plurality of reactor-transformers each having a plurality of legs, one of which has a primary winding adapted to be connected to one phase of a polyphase source of power and a main secondary winding thereon, another leg movable and having an auxiliary secondary winding there-around, and still another leg spaced from the other legs, the last-mentioned leg and the first-mentioned leg of each transformer having yoke ends between which the movable leg thereof is positioned, the last-mentioned legs of each transformer being coupled to form at least one common flux path for all the transformers, the main and auxiliary secondary windings of each transformer being connected in series and to an electrode, the electrodes being positioned to act in conjunctive relation.

2. A polyphase welding system including a plurality of reactor-transformers each having a plurality of legs, one of which has a primary winding adapted to be connected to one phase of a polyphase source of power and a main secondary winding thereon, another leg movable and having an auxiliary secondary winding there-around, and still another leg spaced from the other legs, the last-mentioned leg and the first-mentioned leg of each transformer having yoke ends between which the movable leg thereof is positioned, the last-mentioned legs of each transformer being coupled at least in part by a movable leg to form an adjustable flux-carrying member common to all the transformers, the main and auxiliary secondary windings of each transformer being connected in series and to an electrode, the electrodes being positioned to act in conjunctive relation.

3. For a welding system utilizing a plurality of simultaneously acting cooperative arcs, a plurality of reactor structures, one for each arc, each reactor having a leg positioned with a leg of all the other reactors to form a common flux path, and a movable core leg forming a part of said flux path to simultaneously change the reactive effect of all the reactors.
